[57] **CLAIM**

The ornamental design for an articulated, collapsible sled, as shown and described.

DESCRIPTION

FIG. 1 is a perspective view of an articulated, collapsible sled showing my new design;

FIG. 2 is an enlarged side elevational view of the front section thereof, it being understood that the opposite side is a mirror image of that shown;

FIG. 3 is a top plan view of FIG. 2;

FIG. 4 is a bottom plan view of FIG. 2;

FIG. 5 is a front elevational view of FIG. 2;

FIG. 6 is a rear elevational view of FIG. 2;

FIG. 7 is a fragmentary front elevational view of FIG. 2 with the runner in partially collapsed condition.

The rear section of the sled is identical to the front section shown in FIGS. 2-7.
